UNITED STATES PATENT OFFICE.

JOHN J. GREEN, OF BOONTON, NEW JERSEY.

CARRIAGE MECHANISM.

SPECIFICATION forming part of Letters Patent No. 729,327, dated May 26, 1903.

Application filed June 12, 1902. Serial No. 111,248. (No model.)

To all whom it may concern:-

Be it known that I, JOHN JAY GREEN, a citizen of the United States, residing in Boonton, in the county of Morris and State of New Jersey, have invented certain new and useful Improvements in Carriage Mechanism, of which the following is a specification.

The present invention relates to the carriage mechanism of typographic machines, especially typographic machines of the type-writer class; and its main objects are to provide an improved organization whereby the platen may be readily shifted in either direction from its normal position toward the front 15 or toward the rear of the machine, to provide a construction of the platen and its associated mechanism designed especially to facilitate the various manipulations of which the former is capable, and to provide novel adjustable 20 stop members for limiting the motion of the carriage. These as well as other features embodied in the present improvements are set forth with the aid of the accompanying drawings, in which—

25 Figure 1 is an elevation from the side of a machine of the type-writer class in which there are embodied the features of my invention, certain portions, however, being omitted. Fig. 2 is an elevational view of the carriage mechanism looking from the rear of the machine; and Fig. 3 is a similar elevational view looking from the front of the machine, the carriage mechanism being represented as removed from its position.

30 Similar characters of reference designate corresponding parts in all figures.

The supporting-frame of the machine may be of a desired and appropriate design and construction, comprising in the illustrated 40 form thereof a base B, at opposite sides of which and adjacent to the rear of the machine are secured side brackets b b, connected by a stretcher-bar b' and constituting a subordinate frame by which the carriage and its 45 shiftable bed are supported. This carriage (designated in a general way by C) is capable of being shifted toward the front and toward the rear of the machine relatively to a normal position for the purpose, for instance, of bringing at will the platen, hereinafter referred to, into operative relation with either 50 one of the printing-types of an actuated type-

bar (no type-bars being shown) located upon opposite sides of the type, which is effective to print a character of ordinary composition. 55 To permit of this movement, the bed C' of the carriage is mounted upon guide-rails 2 2, extending between the aforesaid stretcher-bar b' and corresponding lugs b² on the brackets b b. These rails 2 2 are in this instance in 60 the form of cylindrical rods, and the means for mounting the shiftable bed thereon comprises a grooved roller 3; engaging with one rod, and a cylindrical roller 3', engaging with the other, both of these rollers being rotatably mounted upon the bed.

Referring now to the means provided by the present invention for effecting the fore-and-aft or backward-and-forward shifting of the carriage and carriage-bed, two shift-keys 70 are employed, (designated by D and D', respectively.) In the particular organization illustrated the latter of these keys is disposed nearer the front of the machine than the other and when actuated serves to shift the 75 parts toward the rear, operating to effect a movement oppositely to that accomplished by the direct actuation of the other key, and hence while one of the keys serves upon its depression to shift the carriage and carriage-bed rearwardly, on the other hand, when the other shift-key is directly actuated, a forward shifting movement of the parts will result. The construction employed for accomplishing this comprises a shift-lever 4, fulcrumed 80 intermediate its ends by a stud 4' to the left side of the base B and carrying at the end of the forwardly-extending arm the key D', while its rearwardly-extending arm is provided with a lateral projection 4², with the 90 upper edge of which is adapted to contact the heel 5' of a spring-pressed latch 5, pivoted by a pin, such as 5², to the arm 6² of an angle-lever 6. The latch 5 supports the aforesaid shift-key D and is urged by a spring 95 7, connecting the latch with a lug 7' on the angle-lever 6, to a position such that the aforesaid heel 5' is disposed above the lateral projection 4² on the lever 4. This position of the latch is determined by a stop 5³, formed 100 in this instance by bending the upper edge of the latch over the edge of the forwardly-projecting arm of the lever 6. Upon the depression of the shift-key D the first result is

the slipping of the heel 5' off the projection 4², whereupon a stop 5⁴ (formed in this instance by laterally bending the latch) is brought against the lower edge of the arm of the lever 6. Further depression of the key now causes the actuation of the angle-lever 6 and the turning of the same about its pivot 6', thereby communicating motion to the carriage-bed C' through an arm 7 secured there-to and pivoted at its free end to the upwardly-extending arm 6^b of the angle-lever. Suitable stops 8 8', the former being in this instance located upon the upwardly-extending arm of the angle-lever and coöperating with a portion of the framing, serve to limit the backward and forward movements of the angle-lever. It is evident from this construction that while by the depression of the shift-key D the forward movement of the carriage 20 and its supporting-bed may be effected, yet upon the depression of the shift-key D', the motion being then transmitted through the latch 5 to the angle-lever, a reverse movement of the carriage, &c., from their normal 25 positions is accomplished. Leaf-springs 8" 8" tend to return the shifted carriage to and maintain the same in its central position. A spring 9 may be advantageously combined with the lever 4 to assure the return of the lever after actuation. While the carriage and its bed are as a whole shiftable toward the front and toward the rear of the machine, the platen itself is capable of a longitudinal step-by-step movement for letter and word 30 spacing as the type-bars (not shown) are successively operated. In the construction herein set forth the carriage C is adapted to move along runways 10 10', comprised in the carriage-bed and extending from side 35 to side of the machine. The roller-platen E is mounted in side pieces 12 12', comprised in the carriage C and rigidly connected at the rear by a stretcher-bar 13, which supports a journalized roller 13', adapted to roll to and fro longitudinally of the runway 10, while at the 40 front there is disposed a guide-bar 14 of the carriage, having a V-shaped groove in its lower surface, in which and in a corresponding groove in the runway 10' are one or more anti-friction carriage-supporting balls 15. The 45 longitudinally-movable carriage may be confined to a free longitudinal movement on the runways 10 10' in any suitable manner. In this instance an inverted-L-shaped finger 16, secured to the runway 10, has its laterally-bent end disposed above the stretcher-bar 13, while at the front similar L-shaped fingers 16' 16', secured to the runway 10', coöperate with the upper surface of the guide-bar 14 to 50 prevent the accidental vertical dislodgment of the parts. The supporting-journal of the roller-platen E is extended at the left and provided with a thumb-wheel 17, while rigid with the journal of the platen there is a 55 ratchet-wheel 18, disposed in this instance exteriorly of the side piece 12', in which the platen is journalized. A pawl 18', carried by

a pawl-carrier 18², journaled concentrically with the platen, is adapted to engage with the teeth of the ratchet-wheel 18 for the purpose of effecting the line-spacing, a finger-piece 18³ being provided on this pawl-carrier for facilitating its manipulation. The pawl-carrier is drawn to its retracted position by a spring 19', which engages at one end with a lug 19 of the side bracket 12' and at the other end with a projection 19² upon the pawl, the action of the spring tending not only to retract the pawl-carrier, but also to draw the pawl into engagement with the ratchet-wheel. 70 When the pawl-carrier is in its retracted position, however, the pawl does not engage with the ratchet-wheel, as clearly shown in Fig. 1, the pawl being held away from the ratchet-wheel by a pawl-lifter 20' in the nature of a projection on the side frame 12', and with which engages a laterally-projecting finger 20² on the pawl. The platen is thus left free to be rotated by hand, as in ruling, &c. For limiting the amount of angular movement 75 impartable to the ratchet-wheel, and hence to the platen, in effecting line-spacing a stop 21 is journaled to the side frame 12 in coöperative relation with a stop-arm 21' on the pawl-carrier. Preferably the amount of angular movement impartable to the ratchet-wheel is 80 adjustable for the purpose of changing the space distance between lines. The stop 21 is therefore in this instance held frictionally tight by its pivot-pin 21² and has a plurality 85 of stop-faces 21³, with any one of which the stop-arm 21' may be made to coöperate, while a portion 21⁴ of the side frame 12', bent laterally across the path of the stop-arm, limits the return movement of the pawl-carrier under the tension of the spring 19'. 90

The means for feeding the carriage step by step during the progress of the composition comprises the usual spring-actuated drum 22, journaled in a depending lug 22' on the carriage-bed C' and connected with the carriage by a band 22², encircling the drum and causing the latter to so operate as to maintain the teeth on a ratchet-bar 23 on the carriage pressed against a tooth 24 on an oscillatory frame 24', oscillatable about a journal-pin 25, extending through arms 26 26', depending from the runway 10'. A spring 25', connected at one end to an arm 25' and at the other end to a lug 25³ on the rock-frame, tends to maintain the aforesaid tooth 24 in engagement with the teeth of the ratchet-bar. When, however, as the result of the actuation of the spacer-bar or of a key of the key mechanism (not shown) said rock-frame is swung to one side on its axis, (through a suitable connection, indicated in part and designated by 27,) the tooth 24 is released from engagement with the teeth of the ratchet-bar, while a feed-tooth 28 is simultaneously with this release 110 brought into engagement with the ratchet-bar. This tooth 28 is in this instance mounted to slide in the direction of the carriage movement, and owing to the preponderating 115

force exerted by the spring of the actuating-drum 22 the returning-spring 28' of the feed-tooth is overcome and the carriage feeds forward in the usual manner a step. When the 5 rock-frame swings back and the tooth 24 re-engages with the teeth of the ratchet-bar, the feed-tooth being released springs forward the width of a ratchet-tooth under the action of the spring 28', ready again to perform the 10 feeding action upon the actuation of a key or the spacer. The ratchet-bar 23 is not connected rigidly to the carriage, but has affixed to it side arms 29 29', pivoted at points, such as 29² 29², to the supporting-frames of the 15 platen. A finger-piece 30, secured to the pivoted side arm 29, enables the ratchet-bar to be withdrawn from engagement with the teeth 24 and 28, thus leaving the carriage free to be drawn to the left under the action 20 of the spring of the drum 22 or to be manually shifted in the opposite direction against the tension of such spring. The organization is such that when the aforesaid pawl-carrier 18² is shifted to turn the roller-platen a 25 pin 31, extending from the arm 21' of the carrier, is brought to bear against the finger-piece 30, and as the pawl-carrier continues its movement the side arms are swung backward in such a manner as to disengage the ratchet-bar 30 from the teeth 24 and 28, thus leaving the carriage free to be shifted back and forth longitudinally. Although the ratchet-bar and its side arms are so pivoted as to render the 35 weight of the part effectual in maintaining the engagement of the ratchet-bar with the teeth 24 and 28, I have so combined a leaf-spring 31' with the pin 31 as that when the pawl-carrier is in its normal or unactuated position the ratchet-bar will be spring- 40 pressed downward into its engaging position. (See Fig. 1.)

Ordinarily means will be provided for suitably guiding the paper and creating sufficient pressure on the platen to prevent its accidental rotation. In this instance this means 45 comprises rearwardly-extending arms 33 33 at opposite ends of the platen and pivoted adjacent to the bases of the frames in which such platen is journaled. The rearward ends 50 of these arms are connected by a bar 34, over which the paper may run, while adjacent to the base of such arms a roller 35 is journaled, which may be incased in a compressible covering, such as rubber, in order to increase 55 the bite between it and the platen, this roller being drawn down firmly against the platen by a spring 35². The presser-bar 36, having laterally-bent arms 36' 36', is journaled in the aforesaid arms 33 33, being pressed down 60 upon the surface of the platen by the action of a spring 37, with which engages an angularly-bent portion 37' at the extreme end of the presser-bar and so related as to enable the spring to perform its function in pressing 65 the bar against the platen or holding it off the same when the bar is thrown upward.

A marginal stop adjustable lengthwise of the ways upon which the carriage longitudinally moves is shown, comprising a plate 38, having laterally-projecting guiding-ears 38' 70 38², from the latter of which projects a spring 38³, impinging against the edge of a ratchet-bar 39 and tending to press the edge of a finger-piece 39' on the stop into engagement with the teeth of the ratchet-bar. A face 39² 75 on this stop member is disposed in the path of a portion 41' of an arm 41, pivoted to the aforesaid stretcher-bar 13, this pivoted arm working in a slot 41², formed in the side frame 12', and being provided with a finger 80 portion 41³.

An alarm-bell is designated by 42, the same being mounted at the right of the carriage-bed and being adapted to be struck by a striker 42', pivoted at the rear side of the bed 85 and having a lateral projection 42², with which is adapted to engage a swing-arm 43, preferably weighted at its lower end and having a finger portion 43' extending into the path of a projection 43² upon the carriage. 90

Having described my invention, I claim—

1. The combination with a longitudinally-movable platen of a shift-lever therefor, a second shift-lever adapted to transmit its motion through the first-mentioned shift-lever, 95 and an intermediate connector normally connecting one lever with the other and shiftable to a position in which it is inoperative to transmit motion between the levers.

2. The combination with a longitudinally-movable platen, of a shift-lever for the platen pivoted intermediate its ends and adapted to shift the platen from its normal position in one direction transversely to the line of its longitudinal movement, an independently-actuated lever for shifting the platen in the opposite direction and through which the movement of the first-mentioned shift-lever when actuated is transmitted, and an intermediate connector normally connecting one 110 lever with the other and shiftable when the second-mentioned lever is actuated to a position in which it is inoperative to transmit motion between the levers.

3. The combination with a longitudinally-movable platen, of a shift-lever for shifting the platen from a normal position in one direction transversely to its line of longitudinal movement, an independently-actuated shift-lever for shifting the platen from such 120 position in the opposite direction, and a spring-pressed shift-key-supporting latch mounted upon the second-mentioned lever and in normal operative relation with the first-mentioned shift-lever.

4. The combination with a longitudinally-movable platen, of a shift-lever therefor pivoted intermediate its ends and having a lateral extension at one end, an independently-actuated shift-lever, a latch pivotally 130 mounted upon the second-mentioned lever, and stops for limiting the pivotal motion of

- the latch in opposite directions, said latch being adapted to rest upon said lateral extension.
5. The combination with a shiftable supporting-bed and a platen mounted to move longitudinally thereon, of a shift-lever, a second shift-lever adapted to transmit its motion through the first shift-lever, and an intermediate connector normally connecting one lever with the other and shiftable to a position in which it is inoperative to transmit motion between the levers.
6. The combination with a supporting-bed and a platen mounted to move longitudinally thereon, of a shift-lever for said supporting-bed pivoted intermediate its ends and adapted to shift said supporting-bed from its normal position in one direction transversely to the line of the longitudinal movement of the platen, an independently-actuatable shift-lever for shifting said supporting-bed from such position in the opposite direction and through which the movement of the first-mentioned shift-lever when actuated is transmitted, and an intermediate connector normally connecting one lever with the other and shiftable when the second-mentioned lever is actuated to a position in which it is inoperative to transmit motion between the levers.
30. 7. The combination with a shiftable supporting-bed and a platen mounted to move longitudinally thereon, of a shift-lever for shifting said supporting-bed from its normal position in one direction transversely to the line of longitudinal movement of the platen, an independently-actuatable shift-lever for shifting said bed from such position in the opposite direction, and a spring-pressed shift-key-supporting latch mounted upon the second-mentioned lever and in normal operative relation with the first-mentioned shift-lever.
8. The combination with a shiftable supporting-bed and a platen mounted to move longitudinally thereon, of a shift-key pivoted intermediate its ends and having a lateral extension at one end, an independently-actuatable shift-lever, a latch pivotally mounted upon the second-mentioned lever, and stops for limiting the pivotal motion of the latch in opposite directions, said latch being adapted to rest upon said lateral extension.
9. In a type-writing machine, the combination with a shiftable supporting-bed, of rails extending from the front toward the rear of the machine, a grooved and a cylindrical roller mounted upon said bed and adapted to travel on said rails, a longitudinally-movable platen mounted upon said bed, a shift-key for shifting said bed from a normal position in one direction transversely to the line of longitudinal movement of the platen, a second shift-key for shifting said bed from such position in the opposite direction, and an intermediate connector normally connecting one lever with the other and shiftable to a position in which it is inoperative to transmit motion between the levers.
10. In a type-writing machine, the combination with a shiftable supporting-bed, of rails extending from the front toward the rear of the machine, a grooved and a cylindrical roller mounted upon said bed and adapted to travel on said rails, a longitudinally-movable platen mounted upon said bed, a shift-lever for shifting said bed from a normal position in one direction transversely to the line of longitudinal movement of the platen, an independently-actuatable shift-lever for shifting said bed from such position in the opposite direction, and a spring-pressed shift-key-supporting latch mounted upon the second-mentioned lever and in normal operative relation with the first-mentioned shift-lever.
11. In a type-writing machine, the combination with a shiftable supporting-bed, of rails extending from the front toward the rear of the machine, a grooved and a cylindrical roller mounted upon said bed and adapted to travel on said rails, a longitudinally-movable platen mounted upon said bed, a shift-lever for moving the said bed from its normal position in one direction transversely to the line of longitudinal movement of the platen, said lever being pivoted intermediate its ends and having a lateral extension at one end, an independently-actuatable shift-lever for shifting said bed from such position in the opposite direction, a latch pivotally mounted upon the second-mentioned lever, and stops for limiting the pivotal motion of the latch in opposite directions, said latch being adapted to rest upon said lateral extension.
12. The combination with a shiftable supporting-bed comprising a pair of runways, of a longitudinally-movable platen, a supporting-roller adapted to roll lengthwise of one of said runways, balls for supporting the carriage on the other runway, a shift-key for shifting the bed from a normal position in one direction transversely to its line of movement, a second shift-key for shifting said bed from such position in the opposite direction, and an intermediate connector normally connecting one lever with the other and shiftable to a position in which it is inoperative to transmit motion between the levers.
13. The combination with a shiftable bed comprising a pair of runways, of a platen-supporting carriage mounted thereon, a carriage-supporting roller adapted to travel lengthwise of one of said runways, balls supporting said carriage on the other runway, a shift-lever for shifting said bed from a normal position in one direction transversely to the line of longitudinal movement of the carriage, an independently-actuatable shift-lever for shifting said bed from such position in the opposite direction, and a spring-pressed shift-key-supporting latch mounted upon the second-mentioned lever and in normal operative relation with the first-mentioned shift-lever.
14. The combination with a shiftable bed comprising a pair of runways, of a platen-supporting carriage mounted thereon, a support-

- ing-roller adapted to travel lengthwise of one of said runways, balls supporting said carriage on the other runway, a shift-lever for shifting said bed from a normal position in one direction transversely to the line of longitudinal movement of the carriage, said lever being pivoted intermediate its ends and having a lateral extension at one end, an independently-actuatable shift-lever for shifting said bed from such position in the opposite direction, a latch pivotally mounted upon the second-mentioned lever, and stops for limiting the pivotal motion of the latch in opposite direction, said latch being adapted to rest upon said lateral extension. 15
16. In a type-writing machine, the combination with a shiftable supporting-bed comprising a pair of runways, of rails extending from the front toward the rear of the machine, a grooved and a cylindrical roller mounted upon said bed and adapted to travel on said rails; a longitudinally-movable platen-supporting carriage mounted upon said bed; a shift-key for shifting said bed from a normal position in one direction transversely to the line of longitudinal movement of the carriage; a second shift-key for shifting said bed from such position in the opposite direction, an intermediate connector normally connecting one lever with the other and shiftable to a position in which it is inoperative to transmit motion between the levers; a carriage-supporting roller adapted to roll lengthwise of one of said runways; and balls for supporting the carriage on the other runway. 35
17. In a type-writing machine, the combination with a shiftable supporting-bed comprising a pair of runways, of rails extending from the front toward the rear of the machine, a grooved and a cylindrical roller mounted upon said bed and adapted to travel on said rails; a longitudinally-movable platen-supporting carriage mounted upon said bed; a shift-lever for shifting said bed from a normal position in one direction transversely to the line of longitudinal movement of the carriage; an independently-actuatable shift-lever for shifting said bed from such position in the opposite direction; a spring-pressed shift-key-supporting latch mounted upon the second-mentioned lever and in normal operative relation with the first-mentioned shift-lever; a carriage-supporting roller adapted to travel lengthwise of one of said runways; and balls supporting said carriage on the other runway. 55
18. In a type-writing machine, the combination with a shiftable supporting-bed and a platen mounted to move longitudinally thereon, of a shift-lever for shifting said supporting-bed from a normal position in one direction transversely to the line of its longitudinal movement; a second shift-lever for shifting said supporting-bed from such position in the opposite direction, an intermediate connector normally connecting one lever with the other and shiftable to a position in which it is inoperative to transmit motion between the levers; springs for retracting said shift-levers when actuated; and stops for limiting the motion of the latch in opposite directions. 75
19. The combination with a supporting-bed and a platen mounted to move longitudinally thereon, of a shift-lever for shifting said supporting-bed from its normal position in one direction transversely to the line of longitudinal movement of the platen; an independently-actuatable shift-lever for shifting said bed from such position in the opposite direction; a spring-pressed shift-key-supporting latch mounted upon the second-mentioned lever and in normal relation with the first-mentioned shift-lever; springs for retracting said shift-levers when actuated; and stops for limiting their movement in both directions. 90
20. The combination with a supporting-bed and a platen mounted to move longitudinally thereon, of a shift-key therefor pivoted intermediate its ends and having a lateral extension at one end; an independently-actuatable shift-lever; a latch pivotally mounted upon the second-mentioned lever; stops for limiting the pivotal motion of the latch in opposite directions, said latch being adapted to rest upon said lateral extension; springs for retracting said shift-levers when actuated; and stops for limiting their movement in both directions. 105
